UNITED STATES PATENT OFFICE

2,606,850

SEALING MACHINE AND METHOD

Thomas E. Piazze, Mount Vernon, Ohio, assignor
to Shellmar Products Corporation, Chicago, Ill.,
a corporation of Delaware

Application December 3, 1949, Serial No. 131,030

10 Claims. (Cl. 154—42)

1

This invention relates to bag closing and sealing and is more particularly concerned with improvements in methods and mechanisms for automatically closing the end of a bag and providing the same with a transverse seal.

It is a general object of the invention to provide improvements in methods and mechanisms for conveying a bag in a predetermined path, for automatically closing the top margins of the bag opening and for thereafter sealing the same by a transverse heat seal.

It is a more specific object of the invention to provide an improved method and mechanism for heat sealing the end of a bag which comprises end portions of heat sealable material, which material is characterized by its ability to melt along an edge or fold thereof when subjected to radiant heat and thereafter to cool in an integral bead-like formation along the melted edge or fold.

It is a further object of the invention to provide a method and machine for heat sealing the end of a bag formation which comprises heat sealable material, said material being characterized by its ability, when melted along an edge or fold, to cool in bead-like formation along said edge or fold wherein the material at the end of the bag is brought into flat folded relation to provide a marginal edge or fold extending in a substantially uniform line across the bag end, the marginal edge or fold is subjected to radiant heat sufficient to melt the material along a relatively narrow end area, the melting being confined to said end area by cooling means engaging the folded material inwardly of said area and the melted material is thereafter cooled to form a bead-like closure seam.

It is another object of the invention to provide a method and machine for heat sealing the end of a bag of the type described wherein the bag end is brought into flat folded relation and a reverse fold is formed therein to provide a uniform end edge fold which is melted and cooled in bead-like seam formation.

It is another object of the invention to provide a method and machine for heat sealing the end of a bag of the type described wherein the bag end is brought into flat folded relation and the end is trimmed to provide a uniform end edge which is melted and cooled to form a bead-like closure seam.

It is a further object of the invention to provide a bag sealing machine which comprises, in combination, a conveyor for transporting bags in a generally horizontal path, with the top edges of the respective bags uppermost and in closed

10
5
relation, a radiant heater disposed along the path of movement of the bag and in spaced relation to the uppermost extremities of the tops thereof for melting the material in a marginal transverse area across the respective bag tops and cooling members engaging the bag tops in predetermined spaced relation inwardly relative to the uppermost edges thereof whereby to limit the area of the material melted and provide therein a transverse seal.

15
20
It is another object of the invention to provide a heat sealing machine comprising a pair of traveling cooling bands adapted to engage the top of a bag along a predetermined transverse line spaced below the upper margins thereof and a radiant heat sealer arranged in generally parallel spaced relation above the path of travel of the cooling bands for fusing portions of the bag top extending upwardly of the cooling bands and forming therein a bead-like seal formation.

25
30
It is another object of the invention to provide in combination with a conveyor for transporting a bag with its top edges uppermost along a generally horizontal path, a pair of generally parallel traveling cooling belts arranged in spaced relation to the conveyor and engaging the top of the bag at a predetermined inwardly spaced distance from the uppermost edges thereof and a radiant heating element arranged in generally parallel relation with the cooling belts and spaced above the upper edges of the bag a distance sufficient to melt the upwardly projecting portions of a bag top engaged by the cooling belts and form therein a bead-like seal.

35
40
It is another object of the invention to provide in combination with a sealing machine of the type described a cutting device for trimming the upper margins of the bag top to provide a uniform edge to facilitate formation of the heat seal.

45
It is another object of the invention to provide in combination with the sealing machine of the type described a folding device for folding over marginal portions of a bag top to provide therein a reverse fold with the folded edge uppermost and positioned above the uppermost edges of the cooling belts in the sealing machine.

50
55
It is another object of the invention to provide in a bag sealing machine of the type described a pair of cooling belts adapted to engage the bag top at a spaced distance below the uppermost margin thereof and resilient means for mounting one of the belts relative to the other to provide pressure between the belt surfaces which contact the bag top.

These and other objects of the invention will

be apparent from a consideration of the mechanisms shown by way of example in the accompanying drawings, wherein:

Fig. 1 is a bottom plan view of a sealing machine incorporating the principles of the invention, with the bottom cover members removed therefrom;

Fig. 2 is a cross section to an enlarged scale, taken generally on the line 2-2 of Fig. 1;

Fig. 3 is a side elevation with portions thereof in section;

Fig. 4 is a transverse cross section, taken generally on the line 4-4 of Fig. 1;

Fig. 5 is a perspective view of the top of a bag having a transverse seal applied by the mechanism shown in Figs. 1 to 4;

Fig. 6 is a plan view, partially schematic, of a modified form of the machine;

Fig. 7 is a side elevation of the machine shown in Fig. 6;

Fig. 8 is a cross section, taken generally on the line 8-8 of Fig. 6, to an enlarged scale; and

Fig. 9 is a perspective view of the top of a bag incorporating the transverse seal provided with the mechanism shown in Figs. 6 to 8.

Referring to Figs. 1 to 5 of the drawings, there is illustrated a method and mechanism incorporating therein the principles of the invention wherein a transverse heat seal is applied to the marginal edges of the end of a bag formation, the bag end being formed of a material, such as for example, polyethylene film, which material is characterized by its ability when an edge or fold thereof is subjected to radiant heat to melt along the edges or fold and thereafter to cool in a bead-like formation.

The mechanism comprises a base 10 which may be a metal casting formed in a conventional manner. The base 10 supports in depending relation thereon a sealing mechanism 11 and a bag top folding mechanism 12 which are adapted to operate on bags 13 conveyed beneath the frame 10 by an endless conveyor 14.

The conveyor 14 may be supported in any conventional manner beneath the sealing and folding mechanisms 11 and 12 and operated by a separate driving mechanism (not shown) or it may be driven by the same power device which operates the sealing and folding mechanism. The conveyor 14 is adapted to convey the bags 13 through the folding and sealing mechanisms 12 and 11 with the top marginal portions 15 of the bags 13 in upstanding relation and with opposite walls thereof flattened or brought together on each other, either with or without a bellows fold 16. In the illustrated form a bellows fold 16 is employed to reduce the length of the seal and facilitate the folding and sealing operations.

The bag top folding mechanism 12 is supported partially by a pair of laterally spaced bracket members 17 and 18 which project horizontally at one end of the base 10 and are bolted or otherwise secured thereto. The opposed edges of the brackets 17 and 18 are arranged in spaced relation to the longitudinal center line of the machine providing a slot 19 for receiving the bag top 15.

A pair of cooperating bag top folding members 20 and 21 are secured to the bracket members 18 and 17, respectively. The folder member 20 comprises a relatively long narrow vertical blade extending generally along the center line of the machine and an angular bracket forming

horizontal portion 22 secured to the supporting bracket member 18. The folder member 21 comprises a relatively long narrow blade portion arranged in parallel spaced relation to the blade 20 and having a reversely turned triangular folder portion 23 which progressively folds the upwardly extending bag top 15 downwardly around the folder blade 20 as the bag approaches the sealing mechanism 11. The folder member 21 is secured to the supporting bracket 17 by means of an angle plate portion 24.

The bag top 15 is engaged and carried through the folder members 20 and 21 by a pair of cooperating endless belts 25 and 26 having their inner runs in opposed relation. The belts 25 and 26 are supported on their outer ends on pulleys 27 and 28 which are rotatably mounted on sub shafts 29 and 30 depending from the bracket members 17 and 18, respectively. At their inner ends the belts 25 and 26 are supported on a pair of pulleys 31 and 32 which are rotatably mounted on stub shafts 33 and 34 depending from the base 10 of the machine. The belt 25 is slightly shorter than the belt 26 to facilitate engagement with the bag top 15. A plurality of idler pulleys 35 are arranged in back-up relation to the opposed runs of the belts 25 and 26 to hold the same in gripping relation with the bag top 15.

The bag top 15 is delivered from the feed-in belts 25 and 26 to a pair of cooling and conveying bands 36 and 37. The cooling bands 36 and 37 are supported at one end on the pulleys 31 and 32 which carry the inner end of the feed-in belts 25 and 26. At the other end of the machine the bands 36 and 37 are supported on pulleys 38 and 39 which are mounted on shafts 40 and 41 rotatably journaled in bosses 42 and 43 depending from the base 10. The shafts 40 and 41 extend above the upper surface of the base 10 and are connected in rotatable relation by a pair of gears 44 and 45. The shaft 40 extends above the gear 44 to receive a driving pulley 46 which is connected by a belt 47 with a pulley 48 on a change-speed device 49 which is driven by the motor 50. The motor 50 and accompanying change-speed device 49 may be supported on the upper surface of the base 10 or on a bracket or other structure supporting the base 10 and any accompanying mechanism.

The cooling bands 36 and 37 are arranged with the opposed runs which engage the folded bag top 15 at opposite sides and hold the same in folded relation while it is carried through the machine. The bands 36 and 37 are cooled by engagement with a pair of elongate cooling members 51 and 52. The cooling element 51 is supported by bolts 53 engaging bosses 54 depending from the base 10 and having a spacer member 55 to position the cooling member 51 in proper relation to the band 36. Hose connections 56 are preferably provided at opposite ends of the member 51 to supply the same with a cooling fluid. The cooling member 52 is resiliently supported relative to the cooling member 51 being secured to a plate 57 which extends parallel to the base 10 beneath the same and which is slidably supported thereon by means of a headed bolt 58 which is slidable in a slot 59 in a supporting plate 60 which is secured to the base 10. The plate 57 is recessed or cut away at its opposite ends and the longitudinal edges of the recessed ends are engaged by compression springs 61 which are mounted in recesses in blocks 62. The blocks 62 are secured

in fixed relation on the supporting plate 60. The cooling member 52 is also preferably provided with hose connections 63 at opposite ends for connecting the same to a supply of cooling liquid or other cooling medium. Other means for maintaining the cooling members at the desired cooling temperature may be employed.

A radiant heating member 64 which may be an electrical resistance wire, or the like, is mounted in a longitudinally extending recess 65 in a heat insulating block 66 which is secured by means of a bracket 67 to a depending portion 68 on the base 10 and extends in parallel relation to the upper edges of the cooling bands 36 and 37 with the element 64 at a predetermined distance above the same. The heating element 64 is connected to a current supply with suitable temperature control devices.

The top edge of the bag after it is folded over by the folding mechanism 12 is carried through the machine between the cooling bands 36 and 37 in spaced relation to the heating element 64 and the uppermost edge thereof which extends above the bands 36 and 37 is subjected to radiant heat by the element 64 throughout its length. The bag travels at a speed which permits the folded top edge to be fused or melted by the heat from the element 64. The bag top material is cooled where it is contacted by the bands 36 and 37 which limits the extent of the melted portion to a relatively narrow transversely extending area. As it passes beneath the heating element 64 the fused or melted edge forms into a bead which cools when it progresses beyond the element 64 and forms an integral bead-like seal 69 (Fig. 5). The sealed bag is released from the machine as the top passes from between the cooling bands 36 and 37 at the discharge end of the machine and is carried away by the conveyor 14.

Referring to Figs. 6 to 9, there is illustrated a modified form of the invention in which the mechanism is shown partially schematic. In this form, a pair of metal bands 70 are arranged in parallel relation and supported on longitudinally spaced pairs of end pulleys 71 and 72 which are mounted at opposite ends of a supporting base 73 on pairs of depending shafts 74 and 75, respectively. The pulleys at either end may be driven by power mechanism of the same character as shown in connection with the preferred form of the device. The opposed inner runs of the metal bands 70 are guided by a plurality of pressure rollers 76 arranged on opposite sides of the bands 70 along the center line of the machine.

The bags 77 to be sealed are carried on a parallel conveyor in the same manner as in the preferred form which operates in timed relation to the movement of the bands 70. The folded or collapsed tops 78 of the bags 77 pass between the pulleys 71 at the receiving end of the machine and are engaged between the opposed runs of the bands 70.

A pair of slitting wheels 79 and 80 are arranged above the bands 70 and spaced inwardly of the receiving end of the machine. The slitting wheels 79 and 80 are mounted on shafts 81 and 82 depending from the base 73. They engage the bag top 78 at a predetermined spaced distance above the upper edges of the bands 70 and trim the top thereof to provide a uniform top edge 83. The waste material trimmed from the top of the bag may be conveniently removed by a belt 84 which engages at one end in a groove 85 in the slitting wheel 79. The belt 84 engages a pulley 86 depending from the base 73 and driven along

with the trimming wheels 79 and 80 at the speed of the bands 70. As the bag top 78 moves beyond the trimming wheels 79 and 80 it passes beneath a radiant heating device 87.

5 The radiant heating device 87 (Fig. 8) comprises a heat resisting block 88 having a longitudinal slot or groove 89 in its bottom face and a suitable heating element 90 positioned in the groove 89 in spaced relation above the upper edges of the bands 70.

10 A pair of cooling devices 91 are arranged on opposite sides of the bands 70 along the radiant heating device 87 and in spaced relation below the same. One of the cooling devices 91 is urged toward the other by springs 92 seated in recesses 15 in supporting blocks 93 fixed to the base 73. The cooling devices 91 are provided with hose connections 94 for supplying the same with a cooling liquid. The cooling devices 91 hold the bands 70 in engagement with the top 78 of the bag. A relatively narrow marginal portion of the bag top 78 extends above the bands 70 which is fused or melted by the radiant heating device 87.

20 As the bag 78 passes beyond the radiant heating device 87 it moves beneath a seam cooling device 95 which is spaced sufficiently far above the upper edge of the bands 70 to avoid contact with the projecting melted or fused seam forming portion 96 of the bag top 78. The cooling device 25 95 may be in the form of a tank with a circulated cooling medium of any desired character. After the bag 78 has passed beneath the cooling device 95 it is discharged from the machine as it passes between the end pulleys 72.

30 The sealed bag 77 as shown in Fig. 9 is provided along the upper margin of the top portion 78 with a seam 96 which is integral with the material forming the walls of the bag and which is bead-like in formation.

35 40 In both forms of the machine which are illustrated the extent of the seam is controlled by varying the amount of material permitted to extend above the cooling belts. The material which forms the seam is held in closely contacting relation by the cooling belts as it is subjected to the radiant heat. The melting of the material to form the seam tends to eliminate the effect of any small particles of the contents of the bag which might adhere to the walls during the filling 45 50 operation.

55 60 While the mechanism is particularly adapted for sealing bags formed of polyethylene film material, it may be used for sealing bags of any material having similar melting or seam forming characteristics. The top of the sealed bag is provided with a transverse seam which is integral with the bag material, which is bead-like in formation and which is of substantially uniform cross section and strength across the full width of the bag top.

65 70 The mechanism may be used also to form a seal or seam on empty bags or to join the edges of two or more pieces of sheet material, the cooling belts being adapted to convey the material along beneath the radiant heating device in proper relation to insure that the material will be properly melted to form the bead-like seam.

75 In the illustrated forms of the machine the bags or other work being sealed are carried along with the edges of the material to be sealed uppermost, but it will be understood that the mechanism may be otherwise arranged relative to the work. It may be positioned so that the work is carried on one side or above the mechanism. In the latter

position the mechanism would merely be inverted.

I claim:

1. In a bag top sealing machine, means for conveying a filled bag in a substantially horizontal direction with the bag in upright position and its open top uppermost, means for bringing opposite walls of the top of the bag into flat folded relation, cooling bands mounted for horizontal movement and arranged to engage the bag top with a relatively narrow portion thereof projecting above the upper edges of said bands, and a radiant heating element arranged in generally parallel vertically spaced relation to the upper edges of said bands whereby the projecting portion only of said bag top is fused into a bead-like formation upon being conveyed beneath said heating element.

2. In a bag top sealing machine, means for carrying a filled bag forward in a substantially horizontal direction with the bag in upright position and its open top edge uppermost, means for bringing opposite walls of the top of the bag into flat folded relation, means for forming a transverse fold in the marginal portion of the bag top, a pair of cooperating relatively narrow band members mounted for horizontal movement and arranged to engage the folded portion of the bag top with a relatively small portion of the fold projecting above the upper edges of said band members, and a radiant heating element arranged in generally parallel vertically spaced relation to the upper edges of said band members whereby the projecting portion only of said fold is fused into a bead-like formation when said bag is carried forward beneath said heating element.

3. In a bag top sealing machine, means for conveying a filled bag in a substantially horizontal direction with the bag in upright position and its top edge uppermost, means for bringing opposite walls of the top of the bag into flat folded relation, means for forming a transverse fold in the marginal portion of the bag top, endless traveling metal belts mounted for horizontal movement and arranged to engage the folded marginal portion of the bag top with a relatively small portion of the fold extending above the upper edges of said belts, a radiant heating element arranged in generally parallel vertically spaced relation to the upper edges of said belts, and means adjacent said heating element for cooling said belts whereby the portion of said fold extending above said belts is subjected to heat from said heating element as the bag is conveyed beneath the same.

4. A bag top sealing machine comprising means for carrying a filled bag forward in a substantially horizontal direction with the bag in upright position and its top portion in flattened upstanding relation, a pair of endless traveling bands mounted for horizontal movement and arranged with confronting runs engaging the bag top on opposite sides with a relatively narrow marginal area of the bag top projecting above the upper edges of said bands, resilient means for urging the confronting runs of the bands into engagement with the bag top, and a radiant heating means extending in vertically spaced relation to the upper edges of said bands, whereby the projecting marginal portion of said bag top is fused into a bead-like formation when it is carried beneath said heating means.

5. In a bag top sealing machine, a conveyor for carrying a filled bag along a predetermined path

with the bag in upright position and its top uppermost, means to bring the top marginal portions of said bag into flat engagement, means to trim the uppermost portion of said bag top along a uniform line extending transversely of the bag, cooling belts having opposed runs for engaging said bag top on opposite sides and in vertically spaced relation to the upper extremity of the trimmed edge of said bag top as said bag is carried along a portion of its path, and a radiant heating device arranged along said portion of the path of travel and in spaced relation to the upper extremity of said bag edge.

6. In a bag top sealing machine wherein a filled bag is carried in a substantially horizontal direction with the bag in upright position and its open top uppermost, a pair of cooperating endless belts having opposed runs thereof arranged for bringing opposite walls of the top of the bag into flat folded relation, a second pair of endless bands arranged to engage the bag top between opposed runs thereof with a relatively narrow portion of the bag top projecting above the upper edges of said bands, cooling members resiliently engaging said second pair of endless bands and radiant heating means for melting the projecting portion of said bag top, whereby the projecting portion only of said bag top is fused into a bead-like formation.

7. In a bag top sealing machine, means for conveying a filled bag in a substantially horizontal direction with the bag in upright position and its open top uppermost, means for bringing opposite walls of the top of the bag into flat folded relation, means for engaging the flattened top of the bag along a line transversely of the same to form thereon a uniform marginal edge, cooling bands, means for mounting said cooling bands for horizontal movement into engagement with said bag top at a predetermined distance below the top marginal edge thereof whereby a relatively narrow marginal area of said bag top projects above the upper edges of said bands, and a radiant heating element arranged in generally parallel vertically spaced relation to the upper edges of said bands whereby the projecting portion only of said bag top is fused into a bead-like formation upon being conveyed beneath said heating element.

8. In a bag top sealing machine, means for carrying a filled bag forward in a substantially horizontal direction with the bag in upright position and its open top uppermost, means for bringing opposite top wall portions of the bag into flat folded relation, means for engaging the top portion of the bag along a line transversely of the same to form a uniform top marginal edge thereon, a pair of cooperating narrow band members, means mounting said band members for engagement with the bag top along a line below the top marginal edge with a relatively small marginal area of the bag projecting above the upper edges of said band members, a radiant heating element, and means for mounting said heating element in generally parallel vertically spaced relation with the upper edges of said band members whereby the projecting portion only of said bag top is fused into a bead-like formation when said bag is carried forward beneath said heating element.

9. In a bag top sealing machine, a conveyor for carrying a filled bag along a predetermined path with the bag in upright position and its top uppermost, means to bring the top marginal portions of said bag into flat engagement, a

slitting wheel arranged to trim the top portion of said bag top along a uniform line extending transversely of the bag, cooling belts having opposed runs engaging said bag top on opposite sides and in spaced relation inwardly relative to the extremity of the trimmed top of the bag as it is carried along a portion of its path, and a radiant heating device arranged along said portion of the path of travel and in spaced relation outwardly relative to the extremity of the trimmed edge of said bag top.

10. In a bag top sealing machine, means for carrying a filled bag forward in a substantially horizontal direction with the bag in generally upright position and its open top uppermost, means for bringing opposite top wall portions of the bag into flat folded relation, a pair of slitting wheels arranged to trim the top portion of the bag along a line transversely of the same to form a uniform top marginal edge thereon, a pair of relatively narrow band members, means mounting said band members for horizontal movement into engagement with the bag top along a narrow line spaced below the trimmed edge thereof with a relatively small marginal area of the bag pro-

5

10

jecting above said band members, a radiant heating element, and means mounting said heating element in generally parallel vertically spaced relation with said band members whereby the portion of said bag top projecting above said band members is fused into a bead-like formation when said bag is carried forward beneath said heating element.
